Attorney

UNITED STATES PATENT OFFICE.

SIDNEY C. VINCENT, OF BALTIMORE, MARYLAND, ASSIGNOR, BY MESNE ASSIGNMENTS, TO CITIES ILLUMINATING COMPANY, OF NEW YORK, N. Y., A CORPORATION OF NEW YORK.

GAS-COCK.

1,313,140.

Specification of Letters Patent.

Patented Aug. 12, 1919.

Application filed June 9, 1916. Serial No. 102,648.

To all whom it may concern:

Be it known that I, SIDNEY C. VINCENT, a citizen of the United States, residing at Baltimore, State of Maryland, have invented 5 certain new and useful Improvements in Gas-Cocks, of which the following is a specification.

This invention relates to improvements in gas cocks.

10 The primary object of the invention is to provide a cock which, while especially adapted for use in connection with street lamps, nevertheless, is well adapted for house or indoor use.

15 In the use of a device of this character under present lighting conditions, it is desirable to embody in the cock, various characteristics, whereby it may be adapted for use in connection with a pilot-burner, and to 20 provide means whereby when an inverted mantle is used to insure invariable lighting of the light at such mantle, rather than at the "bunsen" which is an undesirable result that frequently occurs unless provisions are made 25 against it.

A further object is the provision of means for controlling the gas supply to feed the pilot either continuously, as where the pilot burns for twenty-four hours, or both when 30 the main supply of gas is on and the light lighted, or at such times only when the gas is extinguished, or the main supply of gas cut off.

35 A further object of the invention is to combine in a single structure, means for operating either a twenty-four hour pilot, or a pilot which is only lighted when the main supply of gas is turned on, and a means for insuring the proper lighting of the lamp 40 when an inverted mantle is employed, and the invention further contemplates provision of means for tensioning the valve operating the lever, so that it will remain positively in either of its extreme positions, thus obviating 45 the objections incident to the lever being jarred from a set position by vibrations incident to the lamps.

In the drawings—

Figure 1 is an edge elevation of the 50 burner;

Fig. 2 is a transverse central section thereof,

Fig. 3 illustrates a series of positions of the valve, and

Fig. 4 is a modified form of the cock 55 wherein an inverted mantle is employed.

The numeral 1 designates the body proper, which is preferably cast with a lateral extension 2 having a pilot-channel 3 terminating short of the bottom of the extension. 60 This channel is internally threaded at its upper end for the reception of the pilot tube 4. Within the extension 2, and at right angles to the pilot-channel are two smaller ducts 5 and 6 both of which communicate 65 with the pilot-channel while the channel 5 communicates with the valve-bore 7, of the cock, and the duct 6 communicates with the main supply channel below the valve or cock 9, which channel runs centrally through 70 the body entering the valve-bore at its upper end, and leading downward, opens into a supply chamber 10, the walls of which are internally threaded as indicated at 11, for attachment to a source of gas supply. The 75 numerals 12 and 13 designate two needle-valves, both threaded into the extension 2, and adapted to control supply of gas from the body proper to the pilot-channel 3, as will be more particularly described farther 80 along.

The numeral 14, designates another lateral extension of the cock which is provided with a flush channel 15, communicating with a small duct 16, whose inner end communicates with the valve-bore 7. 85

The flow of gas from the valve-bore to the channel 15 is controlled by a needle-valve 17 threaded into the extension 14 in the same manner as the valves 12 and 13. 90 The upper end of the flush channel 15, (see form shown in Fig. 4,) is threaded for the reception of a flush tube.

The valve 9 is provided with a main channel 22, which is adapted to be brought into 95 and out of registry with the lower reduced portion 23 of the main channel 21 in the upper part of the body, to establish or cut off, as the exigencies of the case may require, the flow from the gas supply to the mantle or 100 other point of consumption. Intersecting the channel 22, and at an angle thereto I provide in the valve an auxiliary duct 24, which is adapted at times, to register with

the duct 16 so as to establish communication between the gas supply and the flush tube, when the burner is of the type shown in Fig. 4.

5 Since the cock illustrated is intended for connection with a clock or time mechanism I provide the body with offsets 25, and 26 to which are attached plates or brackets 27 and 28 having therein open slots 29 which 10 receive lugs or screws which are carried by the clock mechanism casing, but as this feature constitutes no part of the present invention, it need not be further referred to.

The numeral 30 designates an operating 15 lever clamped to the valve 9 by the usual screw 31 so that when the arm is operated, which may be either, as indicated above, mechanically or by hand, to rock the valve in its seat or bore to establish or cut off 20 communication from the main source of supply, and the various openings leading from the valve seat, as will be apparent. It has been found in practice that no matter how accurately the valve may be fitted in its 25 bore or seat, it will in time, without some provision to prevent it, become loosened and fail to stay in any one of its adjusted positions, due generally, to vibrations the burner is subjected to. To overcome this, I provide 30 the operating lever with an extension 31, of resilient material, which extension is provided at its end with a bearing portion 32 which engages the side of the extension 14, in all positions of the operating lever. This 35 resilient frictional contact with the body serves to keep the lever and valve to which it is connected always in the position to which it has been moved, thus assuring accurate registry at all times between the duct 40 and channel of the valve, and ducts and channels in the body proper.

Referring to the form shown in Fig. 4, the numeral 33 designates a burner tube connected at 24 to the gas cock section. This 45 tube is curved at its upper end as shown, and provided with the mantle-holder 35 of the inverted type. Interposed between the gas cock proper and the mantle is the usual bunsen 36. The numeral 37 designates a 50 flush tube whose lower end communicates with the flush channel 15, the upper end of the tube being let into the tube 33 at a point intermediate between the mantle and the bunsen, so that when the burner is used with 55 this type of mantle the operation of the operating lever will let into the tube 33 above the bunsen, a puff of gas, sufficient to fill the chamber or space in said tube intervening between the mantle and the bunsen, 60 so that the danger of a "flash-back" and consequent lighting at the bunsen is entirely overcome.

Referring particularly to Fig. 1, it will be noted that the parts are so positioned that

there is direct communication between the 65 source of gas supply and the body proper, the duct 5 being closed by the valve. When the operating lever 30 is raised the solid part of the valve will cut off communication with the channel 23, and establish communication with the pilot, as shown in subfigure b. Assuming now that it is desired to use the pilot, at all times, both when the main flow is off, and when it is on; it is only necessary to so adjust the needle valve 13 70 that communication will always be established between the duct 6 and main channel 8. At such time the duct 5 may be open or closed, as may be desired. Now assuming that the cock is used in connection with the 80 inverted type of the burner as illustrated in Fig. 4, and in such a case assuming the parts to be as shown in Fig. 1, when the operating lever is raised, the duct 24 will be brought momentarily in registry with the 85 duct 16 permitting a quantity of gas to pass into the flush channel 15, through it to the flush tube 37. This occurs in the downward opening movement of the operating lever and when the parts are in the position shown 90 in sub figure c, and just prior to the straightening up of the duct 22, in the valve 9.

Having thus described my invention what I claim is:

1. A gas cock comprising a body having a 95 main passage therethrough, and a valve-bore intersecting said passage, a valve in said passage formed with a cut-away portion, and a channel adapted to register with the main passage in the body, and also with an 100 auxiliary duct communicating with a channel in the valve, said body being formed with an extension having therein a flush channel and duct communicating with the valve-bore and with the flush channel, the 105 duct in the valve being adapted to momentarily register with the last mentioned duct in shifting from one extreme position to the other, whereby a puff of gas is permitted to pass through the flush channel, and means 110 for regulating the flow of gas to said flush channel.

2. A gas cock comprising a body having a main passage therethrough and a broad flat outer face, a valve bore intersecting said 115 passage, for controlling the flow of gas through the body, an operating lever secured to the valve, and a transverse elongated resilient arm carried by the lever and frictionally engaging the broad flat outer face of 120 the body portion, whereby the valve is held in its adjusted position.

3. A gas cock comprising a body having a main passage therethrough and having a 125 valve bore therein, a valve in said bore having a cut-away portion and a channel adapted to register with the main passage in one extreme position of the valve, a pilot

duct communicating with the valve bore and adapted to be uncovered by the valve when the channel in the valve is out of registry with the main channel, and said valve having an auxiliary channel communicating with the main channel and with a duct leading to the main burner around the air intake thereof, whereby gas is flashed thereto in the movement of the valve to bring the main

channel into communication with the duct 10 leading to the main burner.

In testimony whereof I affix my signature in presence of two witnesses.

SIDNEY C. VINCENT.
